No. 764,394.

PATENTED JULY 5, 1904.

J. F. SWARENS.

CARRIAGE TOP.

APPLICATION FILED JAN. 18, 1904.

NO MODEL.

FIG. 3.

FIG. 4.

UNITED STATES PATENT OFFICE.

JOHN F. SWARENS, OF OSKALOOSA, IOWA.

CARRIAGE-TOP.

SPECIFICATION forming part of Letters Patent No. 764,394, dated July 5, 1904.

Application filed January 18, 1904. Serial No. 189,553. (No model.)

To all whom it may concern:

Be it known that I, JOHN F. SWARENS, a citizen of the United States, residing at Oskaloosa, in the county of Mahaska and State of Iowa, have invented certain new and useful Improvements in Carriage-Tops, of which the following is a specification.

This invention relates to a novel construction of carriage-top and aims to provide an auxiliary supporting means for the top when thrown back and incidentally to preserve the shape of the same to prevent wrinkling and cracking.

The invention further aims to reinforce the rear bow-arm of the top, so as to obviate all likelihood of breaking of this part in the operation of throwing the top rearwardly.

A special advantage of the invention lies in the fact that the invention is adapted for application as an attachment to carriage-tops at present in use, this being very important in the practical exploitation of an improvement of this character.

For a full description of the invention and the merits thereof and also to acquire a knowledge of the details of construction of the means for effecting the result reference is to be had to the following description and accompanying drawings.

While the essential and characteristic features of the invention are susceptible of modification, still the preferred embodiment of the invention is illustrated in the accompanying drawings, in which—

Figure 1 is a perspective view showing the embodiment of the invention. Fig. 2 is a side elevation showing the top thrown rearwardly. Fig. 3 is a view similar to Fig. 2, showing the top in another of its rearward positions.

Fig. 4 is a detail perspective view, parts broken away, of the attaching-collar secured.

Corresponding and like parts are referred to in the following description and indicated in all the views of the drawings by the same reference characters.

The general configuration or shape of the top is substantially the same as those now commonly in use, consisting especially of the flexible canopy 1 and the supporting-bows therefor. Said top comprises the front arm or bow

2^a and the rear arm or bow 2^b. The upper horizontal hinge-brace 3 and the rear diagonally-disposed hinge-brace 4 are employed in connection with the top, as usual, and so far as above described the top is of a construction similar to the ordinary form used.

My invention resides in the provision of a support or brace 5, which extends from the upper end of the front arm 2^a to a point intermediate the ends of the rear bow 2^b, where it is attached. The brace 5 consists of a brace-bar provided with an opening at the upper end thereof which receives the pivot-pin 6, connecting the upper brace 3 and the arm 2^a. The lower or rear end of the brace 5 is also provided with an opening which receives a projection or pivot 7, extended from a collar 8, which is secured to the rear arm 2^b about intermediate the ends of the said arm. The collar 8 is disposed so as to rest upon the rest 9, which is projected from the carriage when the top is thrown back. The rest 9 in the ordinary type of top receives the entire weight of the top, which is directly sustained by the rear arm 2^b. In the rearward movement of the top to throw the same back the rear arm 2^b in striking the rest 9 is frequently broken, and the disadvantages arising from the above are obvious. In the provision of the attaching-collar 8 the rear arm 2^b is reinforced and strengthened without reference to the co-operative function which the said collar performs in connection with the brace 5. The brace 5 relieves the arm 2^b of the weight of the top when the latter is thrown back, since the said brace 5 occupies virtually a vertical position on rearward disposal of the top 1 and directly sustains the weight which is received upon the rests 9.

Though it is desirable that the top when thrown back be unwrinkled, yet it is preferred that all the variations of the provision of the top as constructed in present use be permitted when my invention is applied thereto. To accomplish the above, the brace 5 is made jointed intermediate its ends, so that the top 1 may be wrinkled by breaking the joint in the usual manner. When wrinkling the top 1, as above set forth, the lower joint-arm of the brace 5 moves in an arc about the rest 9.

as a proximate center, the rests serving as the pivot means for the lower ends of the diagonally-disposed joint-brace 4. When the joint of the brace 5 is broken to permit wrinkling of the top or canopy 1, the capacity of this member as a brace still exists, since same to a certain extent supports the canopy 1 when wrinkled in a manner similar to its supporting function relative to the same when thrown back, as shown in Fig. 2.

The brace 5 does not detract from the appearance of the top whatever and serves as a hand-rest for the occupant or occupants of the vehicle, and all variations in the positions 15 of the top are permitted, as before indicated.

The invention as an attachment is very inexpensive and is susceptible of a very broad application both to carriage-tops now in use and to those sent forth from the manufactory.

20 Having thus described the invention, what is claimed as new is—

1. In combination with a support, a pivoted carriage-top, a rest to receive the weight of the top when thrown back, said top comprising front and rear arms, the rear arm being adapted to engage the rest, and brace means between the front arm and that part of the rear arm adjacent the point engaging the rest.

2. In combination with a support, a pivoted 30 carriage-top, a rest to receive the weight of the top when thrown back, said top comprising front and rear arms, the rear arm being adapted to engage the rest, and a jointed brace between the front arm and that part of the rear arm adjacent the point engaging the rest.

3. In combination with a support, a pivoted carriage-top, a rest to receive the weight of the top when thrown back, said top comprising 40 front and rear arms, the rear arm being adapted to engage the rest, and a brace connecting the upper end of the front arm with

that part of the rear arm adjacent the point of engagement of the latter with the rest.

4. In combination with a support, a pivoted 45 collapsible carriage-top, a rest projected from the support to receive the weight of the top when thrown back, said top comprising front and rear arms, the rear arm being adapted to engage the rest, brace means for holding the 50 carriage-top in an upright position, and an auxiliary jointed brace pivotally secured to the upper end portion of the front arm and that portion of the rear arm engaging the rest. 55

5. In a carriage-top, the combination with bows, horizontally and diagonally disposed hinge-braces coöperating with the bows, and a brace connecting the upper end of the front bow and the rear bow at a point between its ends. 60

6. In a carriage-top, the combination with bows, a reinforcing-collar secured to the rear bow, and a brace connecting the collar and the front bow.

7. In a carriage-top, the combination with 65 bows, a reinforcing-collar secured to the rear bow, and a jointed brace connecting the collar and the front bow.

8. In a carriage-top, the combination with bows, horizontally and diagonally disposed 70 joint-braces coöperating with the bows, a detachable collar secured to the rear bow about intermediate its ends, a projection extended from said collar, and a joint-brace connecting the upper end of the front bow and the collar, 75 the lower end of said brace being pivotally connected with the projection of the collar.

In testimony whereof I affix my signature in presence of two witnesses.

JOHN F. SWARENS. [L. S.]
